[57] CLAIM

The ornamental design for a combined clock and picture frame, substantially as shown and described.

DESCRIPTION

FIG. 1 is a perspective view of a combined clock and picture frame showing my new design;

FIG. 2 is a front elevational view thereof.

FIG. 3 is a top plan view of the design, the bottom plan view being identical.

FIG. 4 is a right side elevational view thereof, the left side being a mirror image; and

FIG. 5 is a rear elevational view thereof.
